STOKER CONTROL

Wilfred Almon Hare, Windsor, Ontario, Canada

Application April 29, 1949, Serial No. 90,466

1 Claim. (Cl. 236—46)

1

This invention has to do with a stoker control, and it is concerned particularly with the control of a stoker mechanism for supplying solid fuel, such as coal, to a furnace for heating a building such as a residence.

The general object of the invention is to provide a system of control which may be placed under the combined controlling influence of the temperature in the building and the temperature outside the building. The arrangement is such that the user may, by selection, place the controlling factor subject to the outside temperature into and out of operation. A further object is to provide an improved arrangement for causing intermittent operation of the stoker, independently of the temperature controls, to thus maintain the fire in the furnace. A further object is to provide a control system where controlling elements are positively driven as by means of a synchronous motor.

Fig. 1 shows a system with some parts diagrammatically illustrated, and illustrating the electrical wiring of the system.

Fig. 2 is a detailed view taken substantially on line 2—2 of Fig. 1 showing brush and modulator structure.

The furnace is generally illustrated at 1 and the stoker is generally shown at 2, the stoker being arranged to supply fuel and air to the furnace with the fuel, usually coal, passing through a conduit 3. The stoker is driven by a suitable electric motor 4. Details of the furnace and the stoker need not be shown as these details are subject to wide variation. A wall of a building is illustrated at 6 and it will be understood that the stoker and furnace are suitably located inside the building, the wall 6 being an outside wall thereof.

The main electric power line for driving the motor 4, and which may be 110 volts of the usual alternating current, is illustrated by conductors 10 and 11 which lead from a suitable source of power and one line, such as the line 11, may lead directly to the motor 4 as indicated. In the line 10, is a line switch 12 by means of which the entire system may be placed into and out of operation and from the line switch 12 the line 10 leads to a suitable thermostat 15. This thermostat is usually placed in a suitable location in the building and it embodies a switch 16 which is opened and closed in accordance with temperature requirements.

Extending from the thermostat is a conductor 17 equipped with a double throw switch 18. This switch may be manipulated to make a connection

2

with contact 19 or contact 20 as elected by the user and extending from the contact 19 is a conductor 22 which is connected to the driving motor 4. A conductor 23 extends from the contact 20 to what may be termed a modulator and conductor 24, which is connected to the line 22, also extends to the modulator.

A line 26 connects into the power line 10 in advance of the thermostat and it extends to a synchronous motor 27 while another line 28 connects the synchronous motor with the power line 11. A line or conductor 29 extends to a hold fire device, this line 29 being conveniently connected to line 26, in turn connected to the power line 10, and a conductor 30 extends from the hold fire device and connects to the line 22 leading to the driving motor.

The synchronous motor 27 is associated with a power transmitting mechanism generally illustrated at 33 which is a reduction gearing for driving a shaft 34 mounted in suitable bearings 35, and the modulator and the hold fire device are mounted on the shaft 34. The arrangement, preferably and advantageously, is such that the shaft 34 rotates very slowly, as for example, two revolutions per hour. The modulator is in the form of a drum generally shown at 40 and it has thereon a contact or conductor of tapered form as shown at 41, which constitutes part of the surface of the drum while the remainder of the surface, as shown at 42, is of non-conductor material, such as a plastic or hard rubber. The contact 41 has a continuous ring like portion 43 at one end of the drum. The modulator construction is somewhat in the nature of a commutator.

The line 24 connects with the modulator through the means of a brush 43 which contacts the continuous ring portion 43, while the line 23 connects with the modulator as by means of a brush 44. The brush 44 is adjustably mounted, for which purpose it may be slidably mounted on a supporting rod like element 45, and the brush 44 is under control of the outside temperature. As representative of such a control, there is a lever 46 connected to the brush as by means of a link 47. The temperature sensitive element outside the building is represented as in the form of a bulb 50 mounted on the outside of the wall and protected by a covering 51. This bulb may be of the usual type sealed with an expandable fluid therein and a tube 53 extends through the wall 6 and connects to an expandable and contractable chamber, such as a bellows 54. It will be appreciated that as the outside temperature rises and falls that the fluid in the bulb 50, which also

fills the expandable chamber, expands and contracts thus rocking the lever 46 and shifting the brush 44 along the support 45. The bellows is connected to the lever 46 by a link or rod 55 and if desired, a spring 56 may be employed as an aid in shifting the lever 46 when the bellows contracts.

The hold fire device is of similar construction in that it embodies a drum 60 mounted on the shaft 34, having some of its surface of non-conducting material 61 and some of its surface of contacting material of tapered form as at 62. The contact material preferably has an unbroken circumferential ring or band at one end of the drum as illustrated at 63 with which a brush 64 contacts, the brush 64 being connected to the line 29. There is an adjustable brush 65 also for contacting the drum 60, the same being shown as pivoted at 66 and adjustable on its pivot as by means of an adjusting screw member 67 against which the brush may be held by a spring 70.

Now, it will be appreciated that as the modulator rotates, an electrical connection is made across the brushes 43 and 44 from time to time as the brush 44 contacts the contact member 41. The length of time that this electrical connection is established depends upon the position of the brush 44. In the drawing it is shown in a rather intermediate position. If the brush be shifted to the right, it comes into alignment with a relatively narrow part of the member 41 and, therefore, the contact is of relatively short duration. If it is shifted to the left, the contact is of relatively longer duration. Accordingly, if the outside temperature is relatively high, the fluid expands, the bellows expand and the brush 44 is shifted to the right while, if the outside temperature is relatively low, the fluid contracts and the brush 44 is shifted to the left. Thus the periodical electrical contact at the modulator is relatively short and relatively long with corresponding relatively high and relatively low outside temperatures.

The hold fire device is similar except it is manually adjustable. When the brush 65 contacts with the member 62 the electrical current is established across the brushes 64 and 65. It will be appreciated that with the hold fire drum 60 rotating constantly as, for example, as two R. P. H. that about every half hour a contact will be made and the duration of this contact can be determined by the position of the brush 65.

The operation of the system is as follows: When the line switch 12 is open, the entire system is inoperative. Upon the closing of the switch 12 the synchronous motor operates constantly thus rotating the modulator drum and the hold fire drum. If the switch 18 be manipulated to make a contact at 19 then the sole control for the operation of the stoker, except for the hold fire device is by the thermostat 15. When the temperature inside the building lowers and the thermostat calls for heat as by the means of closing the switch 16, the circuit is established through the thermostat through line 22 to the stoker motor 4 and back to line 11. The stoker will operate until the thermostat switch 16 is opened by the raising of the temperature inside the building. Periodically, however, the current is established through line 26, line 29, the hold fire device, that is, across the brushes 64 and 65 and thence through lines 30 and 22 to the stoker motor so that the stoker is operated for the selected period of time every half hour. As explained above, this "on" period is selected by the adjustment of the brush 65.

This selection may depend upon the type of coal used as well as other desires of the operator.

When the switch 18 is manipulated to contact at 20, then the system is under the dual control of inside temperature and outside temperature. If the thermostat switch 16 is closed thus calling for heat, the circuit extends through line 23 and to brush 44. The circuit cannot be completed, however, unless it is closed across the brushes 44 and 43. In cold weather the brush 44 may have a position well to the left of that shown and, indeed, the brush 44 may contact with the continuous ring part 48 of the contact member 41. Under this condition, the stoker will operate and cease operation with the closing and opening of the thermostat switch. If the temperature outside is not so cold, the circuit will not be completed until the contact member 41 is in position to engage the brush 44 and then the stoker operates. However, the stoker will cease operating even though the thermostat switch 16 is closed when the contact member 41 moves out from under the brush 44.

Thus will be appreciated that in quite mild weather the system is not liable to overheat. For instance, in mild weather and when the thermostat switch 16 closes the stoker will not operate until the modulator closes the circuit and then it will operate for a period of time corresponding to the outside temperature. This period of operation may be very short and just enough to supply heat in the furnace to provide adequate heat within the building. However, there is usually a delay in the transmission of the heat to the thermostat. If the stoker operated until the thermostat switch 16 opened, the residual heat in the coal fire causes an overheating within the building. However, with the present invention, the furnace operates for only a short time in mild weather and then ceases operation but the fire in the furnace continues burning and after the usual lag period or delay the heat is transmitted to the thermostat and it opens. In a similar manner overheating is prevented in medium weather when the brush 44 is in an intermediate position because the stoker can operate for only the period determined by the modulator.

While the details of the structure of the various parts may vary, it is preferred that a quick break in the electrical circuit be made at the modulator when the contacting member 41 moves out from under the brush 44. One structure for accomplishing this is illustrated in Fig. 2 where the contact member 41 has its outer surface on a greater radius than the surface of the non-conductor 42. With the modulator rotating in the direction shown by the arrow, the trailing edge of the contactor 41 may be undercut as shown at 41a, so that when the brush 44 drops off the same, a quick non-sparking disconnection is made. The end of the brush may be angled or tapered also as shown at 44a. A similar arrangement may be used on the hold fire drum.

I claim:

A control system for a stoker for supplying solid fuel to a furnace for heating a building wherein an electric motor drives the stoker, comprising, conductors constituting an electrical circuit for the motor, a thermostat in the circuit adapted to be placed inside the building for closing and opening the circuit upon temperature fall and rise respectively, a drum having tapered contact members, a synchronous motor connected into the circuit for rotating the drum, a

shiftable contact element for engagement with the contact members on the drum, the element and drum being connected in the circuit in series with the thermostat, a temperature sensitive element for location outside the building, a closed fluid system connected to the sensitive element and including an expandible and contractable chamber inside the building, means connecting the said chamber to the shiftable element, for shifting the same in accordance with the outside temperature to thus variably control the length of the periods in which the circuit to the motor is maintained closed in accordance with the outside temperature, another drum with tapered contact members therein rotated by the synchronous motor, a shiftable contact arm for engaging the second drum, and said arm and drum being connected into the circuit in parallel with the thermostat, and manual means for adjusting the position of the shiftable arm to thereby vary the periodic closing of the circuit for the motor

independently of the influence of the thermostat and temperature sensitive element.
